CHILD'S BUNK BED UNIT OR THE LIKE

Lawrence Santine, 1141 Phyllis Ave., Largo, Fla.

Filed Oct. 14, 1964, Ser. No. 82,177

Term of patent 14 years

(Cl. D5—4)

Fig. 1

Fig. 2

Fig. 3

Fig. 4

FIG. 1 is a front perspective view of a child's bunk bed unit or the like embodying my new design;

FIG. 2, a rear perspective view showing the opposite side from FIG. 1;

FIG. 3, a side elevational view; and

FIG. 4, a top plan view.

I claim:

The ornamental design for a child's bunk bed unit or the like, as shown.
